UNITED STATES PATENT OFFICE.

DELMAR D. KELTNER, OF DES MOINES, IOWA.

PICK.

1,078,585.

Specification of Letters Patent.

Patented Nov. 11, 1913.

Application filed February 24, 1913. Serial No. 751,145.

To all whom it may concern:

Be it known that I, DELMAR D. KELTNER, a citizen of the United States, and resident of Des Moines, in the county of Polk and State of Iowa, have invented a certain new and useful Pick, of which the following is a specification.

The object of my invention is to provide a pick of simple, durable and inexpensive construction, provided with detachable points, parts of said pick being so constructed and arranged that a miner, for instance, may use one head and handle and may easily carry a large number of points.

A further object is to provide such a pick so constructed and arranged that the points may be quickly and easily installed in position or removed from the head, and in which, when the points are secured in position, they are firmly locked.

A further object is to provide such a pick so constructed that a strong, rigid support is provided for the detachable points.

Still a further object is to provide a pick head and detachable points, which head is so constructed and arranged that the handle may be driven into the head and wedged therein by portions of the pick head.

A further object is to provide such a pick with detachable points, the parts being so constructed and arranged that no additional tools are required in removing or installing the points.

My invention consists in certain details, in the construction, combination and arrangement of the various parts of the device whereby the objects contemplated are attained, as hereinafter more fully set forth, pointed out in my claim and illustrated in the accompanying drawings, in which,

Figure 1 shows a side elevation of a pick embodying my invention. Fig. 2 shows a central, vertical, sectional view through the same illustrating the manner in which the removable pick points are secured in the head. Fig. 3 shows a central, transverse, vertical sectional view through the pick head showing the manner in which the handle is mounted therein, and Fig. 4 shows a perspective view of one of the removable points.

In the accompanying drawings, I have used the reference numeral 10 to indicate a portion of the pick handle. I provide a pick head comprising a shank body 11 provided with a socket 11^a to receive the handle

10. The head 11 is provided with opposite extensions 12. The side walls of the shank or body 11 are slightly thicker near the lower or open end of the socket 11^a as shown in Fig. 3, so that the socket 11^a is slightly contracted from side to side at its open end. In the bottom of the socket 11^a I have provided a downwardly extending wedge 13 designed to be driven into the handle 10, for the purpose of separating the end thereof and securely fastening the handle in the pick head. I have also provided in the sides of the body 11 openings which register with each other and are designed to receive a bolt or pin 14, which extends through the side walls of the pick head and through the handle, as shown in Fig. 3, for more securely fastening the head on the handle. In the upper or outer surface of the pick head I have provided a recess 15. In each of the extensions 12 I provide longitudinal recesses preferably rectangular in cross section and communicating at their inner ends with the recess 15.

My removable pick points comprise a point proper 16 and a shank 17, preferably rectangular in cross section, as shown in Fig. 4. The point 16, adjacent to the shank 17 forms a shoulder 18. The shank 17 is designed to be received in the longitudinal opening or recess in the extension 12, as shown in Fig. 2. The outer end of the extension 12 engages the shoulder 18. At the inner end of the opening and in each extension 12 is formed a shoulder 19 which engages the free end of the shank 17 when the parts are firmly secured in position. In the upper surface of each shank 17, near the free end thereof I make a transverse notch 21, the sides of which are preferably somewhat inclined, as clearly shown in Figs. 2 and 4.

For securing the removable pick points in position I have provided a locking cap 22 designed to be received in the recess 15. On the lower surface of the locking cap 22 at each end thereof, is a downwardly extending lug 23 having inclined sides, which lugs are designed to enter the notches 21. The sides of the notches 21 and the lugs 23 are inclined or beveled in order that when the locking cap 22 is pressed tightly into position the sides of the lugs 23 nearest the middle of the cap 22 will engage the adjacent inclined surfaces of the slots 21 and draw the removable pick points inwardly.

for firmly locking them in position and for drawing the shoulders 18 firmly against the ends of the extension 12. In the middle of the locking cap 22 is a hole which registers 5 with the screw threaded hole 27 in the upper end of the head 11. At its outer end the hole in the cap 22 is somewhat enlarged so that when the screw 24 is inserted into the holes above mentioned the head 25 of 10 said screw will enter said enlarged portion until it is flush with the outer upper surface of the cap 22, thereby leaving no parts projecting beyond the pick head. The head of the screw 25 is provided with a notch 26 15 and the upper part of each shank 17 adjacent to the notch 21 at the free end of said shank is designed to be of proper form to be received in the notch 26 so that one of my removable pick points may be used as a 20 screw driver for removing the screw 24 or screwing it into position.

In the practical use of my improved pick, the miner or other user may carry a number of the points 16 and when one is dull may 25 remove the screw 24, and quickly and easily insert another point in the place of the one which has become dulled.

I am aware that picks have been made with detachable points but I know of none 30 having the advantages of mine as set forth herein. The head of the pick is so constructed that the larger part of the weight is in the head. The head may be made of different material and only the points need 35 be of material capable of receiving high temper and being sharpened to a fine point. The advantage of the form of the socket of my pick head is obvious insomuch as the handle may be driven into the head and the 40 shape of the socket and the wedge therein is such that the handle will be very firmly fastened in its position.

I believe that I have special advantages 45 in the form and construction of my removable pick points. The manner in which the points are locked in position in the head gives a very strong and rigid construction, the shoulders 18 being drawn firmly against the extensions 12 and the inner ends of the 50 shanks 17 being firmly locked by means of the locking cap 22. The screw 24 may be operated by means of a small screw driver or by means of one of the extra pick points and where the pick points are used I am 55 enabled to dispense with the use of any extra or special tools in changing my pick points. The construction of the lugs 23 and notches 21 is such that the pick point is always firmly drawn to the inward limit of its 60 movement and locked against any possible movement with relation to the pick head.

The parts of my pick are of simple and inexpensive construction and comparatively few operations are required in their manufacture. I know of no pick so constructed 65 that the points may be removed and others installed in their places so easily and with so little work. Especially in coal and other mines the manufacture and sharpening of picks raises a very important problem. Ordinarily the miner is obliged to carry several heavy picks to and from his work in the entry or room. Where my pick is used the miner need only carry one head and handle and the points are comparatively 75 small so that he can carry a number of them without serious inconvenience. Another problem at the mines is the sharpening of the picks. After each day's use the points must be sharpened and with the ordinary 80 picks the blacksmith can sharpen only a few points at a time on account of the necessity of handling the handle and head in heating the points. Where my picks are used a large number of the points may be 85 placed in the fire at once and it is, therefore, possible to heat more of them than when the ordinary picks are used. At the same time the labor of the blacksmith is largely reduced because he is not obliged 90 to handle the heads and handles of the picks.

It will be understood that variations may be made in the details of the construction of my improved pick without departing from the essential features thereof. It is 95 my intention in the present application to cover any such variations in details of construction which may be included within the scope of the appended claim.

I claim as my invention:

A pick comprising a head having a socket for a handle, opposite lateral extensions provided with longitudinal sockets, said head being provided in its side opposite said first named socket with a recess communicating with the inner ends of said sockets, removable points, each comprising a body having a point and a shank of smaller diameter than said body, designed to be received in one of said sockets and provided with a notch in its side near its inner end, a locking cap received within said recess and provided with downwardly extending lugs for engaging the notches in said point shanks and drawing the removable points inwardly, and means for detachably securing said cap to said head.

Des Moines, Iowa, February 15, 1913.

DELMAR D. KELTNER.
